DOOR LOCK

Ralph H. Wise, Wayne, Mich., assignor to Ford Motor Company, Dearborn, Mich., a corporation of Delaware

Application July 28, 1952, Serial No. 301,239

7 Claims. (Cl. 292—280)

This invention relates generally to door locks, and particularly to door locks of the rotatable bolt type for motor vehicle doors.

An object of the present invention is to provide a door lock mechanism of the type having a rotatable bolt and a rotatable ratchet in which the required functions of a motor vehicle door lock are obtained with a minimum of moving parts. Among the requirements of door lock mechanisms for automotive vehicles are: operation from the exterior of the vehicle both by a handle and by a key operated locking device, and operation and control from inside the vehicle both by means of a handle and a locking button. These objectives and others are obtained by the present construction by the utilization of only three levers, namely, (1) a manually actuated operating lever, (2) a locking lever, and (3) a remote control lever. The operating lever is actuatable from the exterior of the vehicle and incorporates as an integral part thereof a pawl engageable with the rotatable ratchet. The operating lever also has a portion engageable with a blocking portion on the locking lever to prevent unauthorized manual actuation of the operating lever to release the pawl portion thereof from the ratchet. The locking lever is arranged to be actuated by the exterior key actuated device, by the interior lock button, and by the interior remote control lever, and in its locked position prevents actuation of the operating lever. The remote control lever is operated by the interior handle and upon actuation first engages a portion of the locking lever to move the latter out of blocking engagement with the operating lever. Subsequently, the remote control lever engages an arm of the operating lever to release the latter from engagement with the ratchet.

Other objects and advantages of this invention will be made more apparent as this description proceeds, particularly when considered in connection with the accompanying drawings, wherein:

Figure 1 is a perspective view of the door lock mechanism of the present invention, showing certain associated parts in phantom.

Figure 2 is an elevational view, partly in section, of the door lock mechanism as viewed from the interior of the door.

Figure 3 is a vertical cross-sectional view taken on the plane indicated by the line 3—3 of Figure 2.

Figure 4 is an elevational view of the door lock mechanism as viewed from the jamb face of the door.

The door lock shown in the drawings is designed particularly for the right front door of a motor vehicle. The lock mechanism is mounted upon an L-shaped mounting plate 11 having flanges 12 and 13 extending substantially at right angles to each other. The plate 11 is provided with three screw bosses 14 by means of which the mounting plate may be secured to the inner side of the jamb face of the door. The flange 13 of the mounting plate extends along the inner door panel of the vehicle.

The lock is provided with a rotatable toothed latch or rotor 16, Figure 4, formed with six equally spaced pe-

2

ripheral teeth 17, and spaced from the flange 12 of the mounting plate by means of a shield 18. The rotor 16 has an integral shank 19, Figure 2, rotatably mounted in the flange 12 of the mounting plate. The end of the shank 19 is flattened and extends through a correspondingly shaped aperture in a rotatable toothed ratchet 21 and is riveted thereto. The ratchet is likewise formed with six equally spaced peripheral teeth 22 aligned generally with the teeth 17 of the rotor. A sheet metal shield 23 spaces the ratchet from the flange 12 of the mounting plate. The teeth 17 of the rotor 16 are adapted to be engaged by a conventional keeper rigidly mounted on the adjacent door pillar and received between the rotor 16 and the dovetail 24.

Referring now to Figures 1 and 2, a shoulder rivet 26 is mounted upon the flange 12 of the mounting plate 11 and forms a pivotal mounting for the operating lever 27. The operating lever 27 is formed with three integral generally radially extending arms 28, 29 and 31. Arm 28 extends vertically above the pivot 26 and is arranged to be engaged and actuated by a conventional exterior push button 32. Arm 29 extends downwardly from the pivot 26 and constitutes a pawl engageable with the adjacent tooth 22 of the ratchet 21 to prevent rotation of the latter in a clockwise direction as seen in Figures 1 and 2. Arm 31 extends transversely along the inner side of flange 12 of the mounting plate 11 and through a slot 33 formed in the flange 13 of the mounting plate. A tongue 34 is struck out from the flange 12 of the mounting plate and is encircled by a rubber grommet 36 to provide a resilient stop for the arm 31 of the operating lever. A coil spring 37 surrounds the shoulder rivet 26 and has its inner end anchored in a slot formed in the rivet and its outer end 39 extending through a slot 41 formed in the lower end of the operating lever 27 to constantly urge the arm 31 of the lever against the grommet 36.

A locking lever 42 having three arms 43, 44 and 46 is pivotally mounted upon a hollow shoulder rivet 47 extending through the flange 13 of the mounting plate. The rivet 47 is formed with a square opening 48 therethrough adapted to receive the square shank 49 extending from the lock cylinder 51 mounted upon the exterior of the vehicle door for actuation by a key 52. Rotation of the shank 49 by the key accordingly affects a corresponding rotation of the locking lever 42.

As best seen in Figures 1 and 3, the outwardly extending arm 44 of the locking lever 42 is cut away adjacent its upper end to form a shoulder 53 extending, in the locked position of the locking lever 42, beneath the laterally extending arm 31 of the operating operating lever 27. It will be apparent that in this position of the locking lever rotation of the operating lever 27 is blocked and the latter cannot be operated to swing the pawl arm 29 of the lever out of engagement with the ratchet 21. Clockwise rotation of the locking lever 42 under the actuation of the key operated lock cylinder 51 swings the upper arm 44 of the lever out of engagement with the arm 31 of the operating lever 27 so that the latter can be manually operated to release the pawl arm 29 from the ratchet and unlatch the lock mechanism.

Arm 43 of the operating lever 42 extends generally at right angles to the body portion of the lever along the inner side of the flange 12 of the mounting plate 11. The outer end of the arm 43, in the locked position 65 of the locking lever 42 as shown in Figures 1 and 2, lies in the path of rotation of the teeth 22 of the rotatable ratchet 21. Consequently, counterclockwise rotation of the ratchet caused by closing a "locked" door results in swinging the arm 43 of the locking lever upwardly. This upward movement of arm 43 causes a clockwise rotation of the locking lever 42 which continues until arm

43 is moved out of the path of the teeth of the rotatable ratchet, and this movement is sufficient to swing the upper arm 44 of the locking lever out of engagement with the arm 31 of the operating lever 28, thus unlocking the mechanism.

The reference character 54 indicates an over center spring, having one end connected to the arm 44 of the locking lever and the other end connected to the flange 13 of the mounting plate. The spring functions to yieldably hold the locking lever in either its locked or unlocked position until moved by some actuating force.

The third arm 46 of the locking lever 42 extends along the flange 13 of the mounting plate. The outer end of the arm 46 is offset to provide clearance for the lower arm 56 of the remote control bell crank lever 57. The bell crank lever 57 is pivotally mounted by means of a rivet 58 upon the flange 13 of the mounting plate and has integrally formed therewith an upper arm 59 extending along the flange 13 of the mounting plate in overlapping relationship with the end of the arm 31 of the operating lever 27. The lower arm 56 of the bell crank lever is connected by means of a link 61 and crank arm 62 to an inner manually operated handle 63 located remote from the lock mechanism. The lower arm 56 of the bell crank lever 57 is formed with a flange 64 extending at right angles thereto and overlapping the end of arm 46 of the locking lever.

It will be apparent that upon operation of the remote control handle 63 from the interior of the vehicle to swing the bell crank lever 57 in a counterclockwise direction as seen in Figures 1 and 3, the offset flange 64 of the bell crank lever will engage the arm 46 of the locking lever to swing the latter in a clockwise direction from the locked position shown in these views to the unlocked position.

Upon reference particularly to Figure 3, it will be seen that the upper arm 59 of the bell crank lever, in its normal position before operation of the remote control handle 63, is spaced at its outer end a distance above the arm 31 of the operating lever. As a result, the initial rotation of the bell crank lever 57 in a clockwise direction is effective to move the locking lever 42 to its unlocked position prior to engagement of the outer end of the upper arm 59 of the bell crank lever with the arm 31 of the operating lever 27. Further movement of the bell crank lever by the remote control of the interior handle 63 results in swinging arm 31 of the operating lever downwardly and moving the pawl arm 29 of the operating lever out of engagement with the rotatable ratchet 21. Operation of the interior handle 63 thus actuates the locking lever 42 and the operating lever 27 in sequence so that the locking lever is moved out of the path of the arm 31 of the operating lever prior to engagement of the latter by the arm 59 of the bell crank lever.

The locking lever 42 can also be moved between its locked and unlocked positions by means of the usual push button control 66 mounted at the upper end to a rod 67 extending through the garnish molding 68 of the vehicle door and connected at its lower end to the locking lever 42.

It will be understood that the invention is not to be limited to the exact construction shown and described, but that various changes and modifications may be made without departing from the spirit and scope of the invention, as defined in the appended claims.

What is claimed is:

1. In a latch mechanism for a motor vehicle door, a support mounted upon said door adjacent an edge thereof, a toothed rotor rotatably mounted upon said support at one side thereof, a toothed ratchet on the opposite side of said support from said rotor and mounted for rotation with said rotor as a unit, a manually operable lever pivotally mounted upon said support and having an integral pawl portion adapted to engage one of the teeth

of said ratchet to hold said ratchet and rotor against rotation in one direction, and a locking lever pivotally mounted upon said support and having a blocking portion selectively engageable with said manually operable lever to prevent pivotal movement of the latter in a direction to disengage the pawl portion of said lever from said ratchet, said manually operable lever and said locking lever being pivotally mounted for rotation about axes extending substantially at right angles to each other and said locking lever having an arm extending angularly therefrom adapted to engage the teeth of said ratchet, and a second manually operable lever pivotally mounted upon said support and having portions engageable with said locking lever and with said first mentioned manually operable lever to move said levers from their locked to their unlocked positions.

2. In a latch mechanism for a motor vehicle door, an L-shaped mounting plate secured to said door with one flange of said plate positioned adjacent the jamb face of the door and the other flange of said plate positioned adjacent the inner panel of said door, a toothed rotor rotatably mounted upon said first mentioned flange on the outer side thereof, a toothed ratchet on the inner side of said flange and mounted for rotation with said rotor as a unit, a manually operable lever pivotally mounted upon said first mentioned flange and having an integral pawl portion adapted to engage the teeth of said ratchet to hold said ratchet and rotor against rotation in an unlocking direction, said manually operable lever also having an integral arm extending generally parallel to said first mentioned flange and having its end adjacent said second mentioned flange, a locking lever pivotally mounted upon said second mentioned flange for rotation about an axis extending generally at right angles to the axis of rotation of said manually operable lever, said locking lever having an arm extending outwardly from its pivotal connection and provided with a blocking portion adapted to be engaged by the arm of said manually operable lever to prevent pivotal movement of the lever in a direction to disengage the pawl portion of said manually operable lever from said ratchet, and a second manually operable lever pivotally mounted upon said second mentioned flange for rotation about an axis parallel to the pivotal axis of said locking lever, said second mentioned manually operable lever having a first portion adapted to engage said locking lever to swing the latter about its pivotal mounting from its locked to its unlocked position and a second portion adapted to engage the arm of said first mentioned manually operable lever to swing the latter about its pivotal axis in a direction to disengage the pawl portion of said first mentioned manually operable lever from said rotatable ratchet.

3. The structure defined by claim 2, which is further characterized in that the second portion of said second mentioned manually operable lever is normally spaced a sufficient distance from the arm of said first mentioned manually operable lever so that initial rotation of said second mentioned manually operable lever about its pivotal mounting moves said locking lever from its locked to its unlocked position and further rotation of said second mentioned manually operable lever moves said first mentioned manually operable lever from its locked to its unlocked position.

4. In a latch mechanism for a motor vehicle door, an L-shaped mounting plate secured to said door with one flange of said plate positioned adjacent the jamb face of the door and the second flange of said plate positioned adjacent the inner panel of said door, a toothed rotor rotatably mounted upon said first flange on the outer side thereof, a toothed ratchet on the inner side of said first flange mounted for rotation with said rotor as a unit, a manually operable lever pivotally mounted upon said first flange and having an integral pawl portion adapted to engage the teeth of said ratchet to hold said ratchet and rotor against rotation in one direction, said lever having

an arm extending along said first flange and terminating adjacent said second flange, a locking member pivotally mounted upon said second flange and having a blocking portion adapted to engage said arm of said lever to prevent pivotal movement of the latter in a direction to disengage the pawl portion of said lever from said ratchet, said locking member having an arm extending along said second flange, and a bell crank lever pivotally mounted upon said second flange and having a first arm adapted to engage the arm of said locking member and a second arm adapted to engage the arm of said manually operable lever to move said member and said lever from their locked to their unlocked positions.

5. The structure defined by claim 4 which is further characterized in that the arms of said bell crank lever are so arranged with respect to the arms of said locking member and manually operable lever respectively that the initial pivotal movement of said bell crank lever swings the first arm of the bell crank lever into engagement with the arm of the locking member to move the latter to its unlocked position prior to engagement of the second arm of said bell crank lever with the arm of said manually operable lever.

6. The structure defined by claim 4 which is further

characterized in that said locking member has a second arm formed integrally therewith and extending along the first flange of said mounting plate with its outer end located in the path of movement of the teeth of said rotatable ratchet so that rotation of said ratchet in one direction swings the second arm of said locking member about the pivotal connection of said locking member to move the blocking portion of said locking member out of engagement with the arm of said manually operable lever.

10 7. The structure defined by claim 4 which is further characterized in that the second arm of said bell crank lever is normally spaced from the arm of said manually operable lever so that initial rotation of said bell crank lever swings said locking member out of locking position with respect to the arm of said manually operable lever prior to engagement of said last mentioned arm by the second arm of said bell crank lever.
